(57) CLAIM

The ornamental design for a shoe foot bed, as shown and described.

DESCRIPTION

FIG. 1 is a top plan view of a shoe foot bed showing my new design; and,

FIG. 2 is a rear perspective view thereof.

The broken lines immediately adjacent to the shaded area represent unclaimed boundaries of the design. The six circular unshaded regions within the shaded area form no part of the claimed design. The broken lines showing the remainder of the shoe are for environmental purposes only and form no part of the claimed design.
